UNITED STATES PATENT OFFICE.

HAROLD G. RENNER, OF DETROIT, MICHIGAN.

CARBURETOR.

Application filed March 18, 1922. Serial No. 544,768.

To all whom it may concern:

Be it known that I, HAROLD G. RENNER, a subject of the King of Great Britain, residing at Detroit, in the county of Wayne and State of Michigan, have invented a new and useful Carburetor, of which the following is a specification.

This invention relates to carburetors for internal combustion engines, and particularly to the fuel feed control of such carburetors.

The invention has for its object the provision of means for effecting a temporary increase in the quantity of fuel delivered to the carburetor simultaneously with the opening of the throttle to accelerate the engine, and to automatically effect the cutting off of such increase within a predetermined time interval of action independently of a return or closing movement of said throttle.

The invention is especially designed and adapted for application to carburetors of the type disclosed in my patent issued Sept. 12, 1922, No. 1,428,558.

The present invention contemplates, briefly, the employment in connection with means controlled by the throttle for adjusting a primary fuel valve in the outlet of a fuel nozzle, of a reciprocal piston operative in the manner of a dash-pot in the fuel chamber of said nozzle and having a valve stem normally seated in and closing a secondary fuel outlet formed through said primary valve, said piston being urged by a spring toward said primary valve in the opening direction thereof, but being restrained against following said valve under abrupt or rapid movement thereof in such direction, by the retarding action of the liquid fuel displaced by movement of said piston under influence of said spring, hence a sudden opening movement of the primary valve will cause a momentary or time limited opening of the secondary fuel jet supplementing the primary jet in supplying fuel. The duration of action of the secondary fuel supply will be determined by the speed of travel of the piston in advancing the secondary valve stem to its seat in the needle valve and this will be governed by the clearance provided for the passage of the liquid fuel around the piston.

A preferred embodiment of the invention is hereinafter described and illustrated in the accompanying drawing, wherein,

Fig. 1 is a vertical section longitudinally intersecting the mixing chamber and its air inlet of a carburetor embodying the present invention.

Fig. 2 is an enlarged cross section on line 2—2 of Fig. 1, showing a partially opened position of the automatic air and fuel valves.

In these views the reference character 1 designates the mixing chamber of the carburetor and 2 the air inlet thereof, the same together forming a continuous horizontal passage. A flap valve 3 is pivoted upon a pin 4 in the upper portion of said passage, and under idling conditions extends diagonally across the passage in the direction of the flow therethrough, as shown in full lines in Fig. 1. The relatively small current of air which is delivered to the mixing chamber under idling conditions does not exert sufficient pressure upon said valve to overcome the weight thereof. When, however, the throttle is adjusted to permit an increased flow, as when the engine is under load, the resultant air pressure rocks the valve 3 upwardly through an angle proportionate to the increase of flow. It is preferred to form the top of the carburetor casing with an upward extension or dome 5, which will accommodate the valve 3 in its position of maximum elevation. The central portion 6 of the valve forms an arch extending with gradually increasing height from the pivotal extremity to the free end of the valve.

A dash-pot chamber 7 is formed in an integral extension 7' of the carburetor casing beneath the same and inclined at a slight angle from the vertical in the direction of flow through the mixing chamber. A piston 8 is mounted in said dash-pot chamber and is upwardly urged by a coiled spring 9 seated in a cap 9' closing the end of said chambered extension, said piston having a guide flange 10 spaced from the head 11 thereof, the latter having a slight clearance from the wall of the chamber 7, and the former having apertures 12 for the passage of liquid past said piston. Liquid fuel is admitted to the chamber 7 at a point between the piston extremities 10 and 11 through a port 13 opening from a passage 14 leading from a float chamber 15 or other suitable source of supply. A ball check valve 15a seats centrally within the piston 8, closing a by-pass 15b through the head 11 when the piston is

rising but lifting therefrom upon downward movement of the piston to permit the liquid below the head 11 to flow freely through said by-pass and thus relieve the piston from 5 the resistance such as is set up by the displacement of the liquid through the clearance around the piston head as occurs in the rising movement thereof.

A passage 16 primarily providing for 10 a delivery of liquid fuel from the chamber 7 to the mixing chamber, opens into the latter beneath the free end of the air valve 3. Said passage is controlled by a primary fuel valve 17, which is formed with a secondary fuel feed passage 18, therethrough 15 under control of a valve formed by the rounded upper end of a stem 19, integrally rising from the piston 8. The valve 17 is carried by the free end of a rock-arm, comprising 20 a strip of sheet metal 20 extending through the arch of the valve 3 and a leaf spring 21 secured to the other end of said strip and attached by a screw 22 to the top 25 face of the air inlet adjacent the mouth thereof. The connection between said spring and strip may be established by brazing, soldering, or in any other suitable manner. Said spring is stressed to urge the rock-arm 20 upwardly, but not with sufficient 30 force to overcome the weight of the valve 3, which acts upon the rock-arm through a block 23 apertured to engage the rock-arm and having its top rounded to bear upon a plate 24 carried by said valve. The 35 block 23 is adjustable longitudinally of the rock-arm 20 by means of a bar 24^a, arranged beneath said strip and secured at one end to said block. The other end portion of said bar forms a rack 25, engaged by a pinion 40 fast upon a shaft 27 adjacent the spring 21. Said shaft may have an end portion (not shown) projecting exteriorly of the carburetor casing and rotatively actuatable by any suitable means. At 28 is indicated the 45 usual throttle member controlling the outlet from the mixing chamber.

Considering now the operation of the described carburetor, it is to be understood that under idling conditions the valve 3 rests 50 upon the floor of the passage 1, 2, and that the primary fuel valve 17 remains slightly raised from its seat allowing a flow of air and fuel through the comparatively restricted passage formed by the arch member 6. 55 When the throttle 28 is opened more or less, there is a corresponding increase in the flow of air into the mixing chamber, and under such conditions, the valve 3 is rocked upwardly by the pressure of air, as for example, to the position indicated in dash lines in Fig. 1. Such movement of the valve 3 permits the rock-arm 20—21 to likewise swing upwardly responsive to the effort of the spring 21, and consequently the primary 65 fuel valve 17 is withdrawn from the fuel

passage 16 to an extent determined by the angle through which the valve 3 and said rock-arm have been shifted. Under the upward effort exerted by the spring, 9 upon the piston 8 and valve 19, the latter tends to 70 follow the primary valve 17 as the latter is raised from its seat, but owing to the retarding effect of the dash-pot the valve 19 is restrained from immediately following the primary valve when the opening movement of the latter is abrupt or rapid. Consequently, under such conditions the secondary fuel passage 18 is opened and the mixture is enriched by the supplementary delivery of fuel through said passage. If, 75 however, the opening movement of the primary fuel valve is gradual the retarding effect of the dash-pot will not be sufficient to prevent the secondary valve immediately following the primary valve in the opening 80 movement of the latter, thus preventing opening of the secondary fuel passage and the issuance of fuel therefrom.

It will be noted that the functioning of the secondary fuel valve is not dependent upon 90 the specific means disclosed for operating the primary fuel valve, but that said secondary valve will readily function as described in connection with an apertured fuel valve actuated by any suitable means.

What I claim is:

1. A carburetor comprising a mixing chamber, a valve controlling a primary fuel supply to said chamber, said valve having a passage for a secondary fuel supply, a secondary valve normally seating upon the primary control valve to close said passage, means urging said secondary valve to its seat, tending to maintain said passage closed during the opening movement of the primary valve, and means retarding the movement of the secondary valve in the direction of opening of the primary valve.

2. A carburetor comprising a mixing chamber, a valve controlling a primary liquid fuel inlet to said chamber, said valve being formed with a secondary fuel inlet substantially co-axial with the primary inlet, a secondary valve normally seating upon the primary valve to close said inlet therein, a spring normally urging said secondary valve to its seat, tending to maintain the secondary inlet closed during opening of the primary valve, and means retarding the movement of the secondary valve in the direction of opening of the primary valve.

3. A carburetor, comprising a mixing chamber, a valve controlling a primary liquid fuel inlet to said chamber, said valve being formed with a secondary liquid fuel inlet, a follower valve seating upon the first mentioned valve oppositely to the direction of seating of the latter and controlling said secondary fuel inlet, a spring urging said follower valve to its seat in the direction 125 130

of opening of the primary valve, and a dash pot retarding the seating movement of said follower valve.

4. A carburetor, comprising a mixing chamber, a valve controlling a primary liquid fuel inlet to said chamber, said valve being formed with a secondary liquid fuel inlet, a follower valve seating upon the first mentioned valve oppositely to the direction of seating of the latter and controlling said secondary inlet, a piston connected to said follower valve, a liquid fuel chamber in which said piston operates as a dash pot to retard seating of the follower valve, said chamber communicating with said primary and secondary fuel inlets, means for supplying liquid fuel to said chamber, and means within said chamber urging the follower valve to its seat.

5. In a carburetor, a casing having a mixing chamber, and formed with an air inlet and a primary liquid fuel inlet to said chamber, a valve controlling said air inlet responsive to air pressure, a primary valve controlling said liquid fuel inlet, and urged to its seat by said air valve in closed position of the latter, said primary valve being formed with a secondary fuel inlet, a secondary fuel valve seating upon the primary valve in the direction of opening thereof and controlling said secondary inlet, means urging said secondary valve to follow the primary valve when the latter is unseated, and means for retarding such following movement of the secondary valve. 30 35

In testimony whereof I sign this specification.

HAROLD G. RENNER.
